José Arturo Conde, Independence, Mo., assignor to The Vendo Company, Kansas City, Mo., a corporation of Missouri

Filed Mar. 9, 1966, Ser. No. 1,376

Term of patent 3½ years

(Cl. D52—3)

FIG. 1 is a front elevational view of a vending machine showing my new design;

FIG. 2 is an elevational view of one side thereof taken from the left of FIG. 1 and on a reduced scale;

FIG. 3 is a top plan view;

FIG. 4 is an enlarged cross-sectional view taken on line 4—4 of FIG. 1;

FIG. 5 is an enlarged cross-sectional view taken on line 5—5 of FIG. 1;

FIG. 6 is an enlarged cross-sectional view taken on line 6—6 of FIG. 1; and

FIG. 7 is an enlarged cross-sectional view taken on line 7—7 of FIG. 1.

The side opposite to that shown in FIG. 2 is the same in appearance as that shown in FIG. 2.

I claim:

The ornamental design for a vending machine, as shown and described.
